UNITED STATES PATENT OFFICE.

LESLIE M. SNODGRASS, OF MILWAUKEE, WISCONSIN.

KEY-RETAINING DEVICE.

Application filed July 16, 1923. Serial No. 651,885.

To all whom it may concern:

Be it known that I, LESLIE M. SNODGRASS, a citizen of the United States, residing at Milwaukee, in the county of Milwaukee and 5 State of Wisconsin, have invented certain new and useful Improvements in a Key-Retaining Device, of which the following is a specification.

The present invention relates to a device 10 for retaining a key within a lock and has for its principal object to provide a device which may be inserted in the keyhole, holding the key in the keyhole and in a turned position so that the same may not be removed. It is the common practice to provide rather cheap inefficient locks for the rear doors of residences. With this device 15 the key may be inserted into the lock and turned to lock the door and this device inserted into the key hole and locked to the key so that it will be impossible to insert a key into the lock from the exterior and also impossible to pick the lock.

Another important object of the invention 20 is to provide a device of this nature which may be manufactured at a low cost because of its simple and efficient structure and which will be reliable and durable.

With the above and numerous other objects in view as will appear as the description progresses, the invention resides in certain novel features of construction and in the combination and arrangement of parts 35 as will be hereinafter more fully described and claimed.

In the drawings—

Figure 1 is an elevation showing a lock with a key and my device associated therewith,

Figure 2 is a top plan of the structure 40 shown in Figure 1,

Figure 3 is a perspective view of the device, and

Figure 4 is a plan view of the device before the same is bent.

Referring to the drawing in detail it will be seen that 1 designates an ordinary lock provided with the keyhole 2. A key 3 is disposed within the keyhole and turned. 50 My device is inserted in the keyhole under the key and of course prevents the turning thereof. This device is formed preferably from sheet material and the blank is shown in Figure 4. This blank is bent 55 along the line 4 which extends centrally and

longitudinally thereof so as to provide the body 5. The blank is also bent along the lines 6 and provides a slanting portion 7 which terminates in the lip 8. An extension 9 is bent over the lip and both the extension and the lip are provided with apertures as at 10. It will be seen that the lip 8 and its extension 9 will be disposed to house the handle 11 of the key so that a padlock 12 may be inserted through the handle and through the apertures 10.

When the device is assembled as is shown in Figure 1 it will be quite impossible for anyone to remove the key 3 from the outside and therefore quite impossible to pick the lock. This device makes the ordinary door lock quite as efficient as those of a more complicated nature which are far more expensive.

I have described the preferred embodiment of my invention which will give in practice satisfactory and reliable results but it is to be understood that numerous changes in the details of construction may be made without departing from the spirit of the invention or sacrificing any of its numerous advantages.

Having thus described my invention what I claim as new is:

1. A key retaining device of the class described formed from a sheet of material bent upon itself from one end to an intermediate point so as to form a body adapted for insertion in a key hole, and further bent at the intermediate point to provide a slanting portion terminating in an apertured lip substantially co-planer with the upper edge of the body.

2. A key retaining device formed from a sheet of material bent upon itself from one end to an intermediate point so as to form a body adapted for insertion in a key hole, and further bent at the intermediate point to provide a slanting portion terminating in an apertured lip substantially co-planer with the upper edge of the body and an apertured extension provided on the lip for as to overlie the same for the reception of the key bow.

In testimony whereof I affix my signature 105 in presence of two witnesses.

LESLIE M. SNODGRASS.
